Primary Examiner—Susan J. Lucas*Assistant Examiner*—Pamela Burgess[57] **CLAIM**

The ornamental design for a magnetic perpetual calendar, as shown and described.

DESCRIPTION

FIG. 1 is a front elevational view of a magnetic perpetual calendar showing my new design, the undisclosed rear being flat and unornamented; and,

FIG. 2 is a right side elevational view thereof, the undisclosed left side being a mirror image and it being understood that the removable elements are shown detached for clarity of illustration only.
